TYPEWRITING MACHINE

Oscar J. Sundstrand, West Hartford, Conn., assignor to Underwood Elliott Fisher Company, New York, N. Y., a corporation of Delaware

Application December 31, 1940, Serial No. 372,632

4 Claims. (Cl. 197—3)

This invention relates to typewriting machines of the flat platen type in which the platen is movable in a direction substantially perpendicular to its plane to clamp the work sheets in operating position and to release said work sheets. In typewriting machines of the Elliott Fisher type and in certain other machines, the flat platen is movable toward and from the type mechanism or toward and from the work clamping plates located along the side bars of the platen frame to enable the work sheets to be inserted in the machine and to clamp the sheets in operative position.

The primary objects of the present invention are to improve the construction and mode of operation of the platen mechanisms of machines of the above type and to produce a platen mechanism in which the required movements of the platen may be easily produced manually and the mechanism for supporting the platen is greatly simplified as compared with prior mechanisms.

Another object of the invention is to produce an improved construction for movably supporting the flat platen of machines of the above type in which the parts are of relatively light construction, may be more cheaply manufactured and may be more readily assembled than in prior mechanisms.

Another object of the invention is to produce a platen supporting construction for machines of the flat platen type in which the platen may be quickly and easily moved out of operative position and restored to such position by and under control of either the hand or the foot of the operator.

With the above objects in view, the invention consists in a platen mechanism embodying the novel and improved features hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings:

Fig. 1 is an underside plan view illustrating the platen frame, platen and platen supporting mechanism of a machine of the Elliott Fisher type embodying the invention.

Fig. 2 is a view of the mechanism shown in Fig. 1, partly in side elevation and partly in vertical section, taken substantially on the line 2—2 of Fig. 1.

Fig. 3 is a view similar to Fig. 2 showing certain of the parts in different positions.

Fig. 4 is a view in front elevation partly broken away, illustrating certain portions of the mechanism shown in Figs. 1 to 3, inclusive.

Fig. 5 is a detail view illustrating, in rear elevation, certain parts of the platen lowering mechanism, and

Fig. 6 is a detail view in vertical section illustrating the manner in which the supporting levers of the platen mechanism are pivoted on the frame.

In the present application, the invention is illustrated as embodied in a typewriting machine of the Elliott Fisher type such as that illustrated and described in the patent to Foothorap No. 1,904,127, dated April 18, 1933. The machine shown in said patent comprises a substantially rectangular platen frame, a line space frame mounted on the platen frame and movable forwardly and rearwardly on the platen frame and a type head or carriage mounted on the line space frame and movable thereon transversely of the machine in advance and return directions. The platen frame and platen of the illustrated machine have substantially the same construction and arrangement of parts as the corresponding mechanism of the machine disclosed in the above Foothorap patent.

The construction shown in the drawings comprises a platen frame provided with substantially parallel side bars 2 and with front and rear cross bars 4 and 6 connecting said side bars. The flat platen indicated at 8 consists of a substantially rectangular plate mounted for vertical movement in the space between the side bars and the front and rear cross bars of the platen frame. The side bars 2 of the platen frame are provided respectively with clamping plates 10 extending over the side margins of the platen between one or both of which and the platen the work sheets are clamped when the platen is moved to its upper position, the clamping plates serving to limit the upward movement of the platen.

In the present machine the platen is supported in the platen frame and is moved in said frame in directions substantially perpendicular to the general plane of said frame or to the plane of the platen, the several positions of the platen being substantially parallel with each other.

The mechanism for supporting the platen in the frame comprises front and rear supporting levers 12 and 14, all of substantially the same construction and pivoted in a similar manner to the platen frame. The two levers 12 adjacent

the front of the platen are each pivoted to one of the side rails upon a boss 15 formed on a spacing washer 16 secured by a screw 18 to the inner side of the corresponding side bar or rail 2, the lever swinging between the head of the screw and the body of the spacing washer. Each of the levers 14 adjacent the rear of the platen is pivoted to one of the side bars or rails 2 upon a boss on a spacing washer 22 secured by a screw 24 to the inner side of one of the side rails.

In the present construction, the levers 12 are pivoted on substantially coincident horizontal axes as are also the levers 14, and the axes of the levers 12 are substantially parallel with the axes of the levers 14.

The levers 12 and 14 are all connected so that they swing in unison and in the same direction about their respective axes. The levers are arranged to support the platen either in raised or lowered position, upon the arms or portions of the levers extending upwardly beyond their respective pivots, the platen being held down on the levers by gravity at all times during the movements of the levers. The levers are each provided with a surface 26 arranged at a predetermined distance from the center of the lever for engagement with the platen to support the platen in its upper or raised position as shown in Fig. 2 and with a surface 28 arranged at a less distance from the axis of the lever for engagement with the platen to support the same in lowered position as shown in Fig. 3.

The lower ends of the levers 12 and 14 on each side of the platen are connected by a link 30 so that these levers move together and in the same direction about their respective axes. The levers 12 adjacent the front of the platen are each connected by a link 32 with an arm 34, the hub of which is fixed to a rock shaft 36 mounted to turn in bearings in the side bars or rails 2. This connection between the levers 12 and the rock shaft 36, together with the link connection between the levers 12 and 14 on each side of the platen causes the levers 12 and 14 all to swing together about their respective pivots.

Each of the levers 12 and 14 is acted upon by a coiled spring 37 connecting the lever with a pin 38 fixed in the corresponding side bar or rail, these springs tending to swing the levers in a clockwise direction, Figs. 2 and 3, to raise the platen. The levers are swung in the opposite direction to lower the platen by turning the rock shaft 36 in a clockwise direction, referring to said figures.

In order to guide the rear end of the platen during its vertical movements, an angle bracket 39 is secured to the rear cross bar 6 of the platen frame beneath the platen and a pin 40, fixed to and projecting downwardly from the under side of the platen, engages in a slot 41 in the horizontal arm or portion of said bracket to guide the forward end of the platen. An angle bracket 42 is secured to the front cross bar 4 of the platen frame beneath the platen and a pin 43, fixed to and projecting downwardly from the platen, engages in an opening 44 in the horizontal arm of said bracket, to guide the forward end of the platen.

To enable the shaft 36 readily to be turned in a direction to lower the platen, a sleeve 45 is attached by means of a screw 46 preferably to each end of the shaft outside of each side bar or rail 2 and a hand lever 47 is fixed to each sleeve.

Each lever 47 is made from sheet metal and comprises two substantially parallel side plates

48 connected by a cross web 49. These side plates are each provided with an opening 50 in which fits the outer end of the sleeve. The end portion of the sleeve is cylindrical for the greater portion of its periphery, but is formed with a flat surface 52 to prevent the lever from turning on the sleeve. The screw 46 is inserted between the side plates 48 of the lever 47 and its head fits closely to said plates.

In assembling the shaft 36, sleeve 45 and lever 47, the sleeve is applied to the outer end of the shaft and the lever is slipped over the end of the sleeve before the screw 46 is inserted. The insertion of the screw then secures the sleeve to the shaft and the head of the screw holds the lever from movement axially of the sleeve, turning movement of the lever on the sleeve being prevented by the engagement of the flat surface 52 of the sleeve with the correspondingly shaped portions of the side plates of the lever. The rock shaft 36 is held from longitudinal movement in its bearings in the side bars 2 of the platen frame by the engagement of the sleeves 45 with said side bars.

In order to depress the platen, the forwardly projecting arm of one of the hand levers 47 is depressed manually to swing the shaft 36 in a clockwise direction, Figs. 2 and 3. The movement of the hand lever in this direction is limited by means of a pin 54 secured in and projecting laterally from the corresponding side bar 2 of the platen frame which pin is arranged to be engaged by a rearwardly projecting arm 56 on the lever.

As above indicated, Fig. 2 shows the parts in the positions which they assume when the platen is elevated. As shown in this figure, the platen rests upon the surfaces 28 of the platen supporting levers and is held in position by the action of the springs 37, the platen engaging the clamping plates 19 which limit the upward movement of the platen and the corresponding movement of the platen supporting mechanism when no work is in the machine. In the operation of lowering the platen, the forward end of one of the hand levers 47 is depressed until the arm 56 engages the pin 54, thereby swinging the levers 12 and 14 in counter-clockwise directions, Figs. 2 and 3, into the positions shown in Fig. 3.

The swinging of the levers 12 and 14 into these positions, allows the platen to descend to the position shown in Fig. 3 in which it rests on the surfaces 28 of the levers. Upon the release of the hand lever 47, the levers 12 and 14 are swung back in the opposite direction by the coiled springs 37 and the platen is moved upwardly to the position shown in Fig. 2, the upward movement of the platen and the corresponding movement of the platen supporting devices being limited by the engagement of the side margins of the platen with the clamping plates 19 or with the work sheets inserted between the platen and one or both of said clamping plates.

To enable the platen to be depressed by the foot of an operator, the two rear platen supporting levers 14 are connected by means of a cross bar 58 pivoted to the levers by means of pintles 60 projecting from the ends of the bar and each engaging in a bearing formed in the upper portion of the corresponding lever (see Fig. 5) to the rear of its axis.

The cross bar 58 is provided with a centrally located slot 62 in which engages the upper hooked end of a treadle rod 64 the lower end of

which is connected with a suitable treadle (not shown).

With this construction, the levers 14 and with them the levers 12 may be swung in a counter-clockwise direction, Figs. 2 and 3, to allow the platen to be depressed, by the depression of the treadle and treadle rod, the movement of the levers and the downward movement of the platen being limited by the engagement of the arms 58 of the levers 47 with the pins 54. Upon the release of the treadle and treadle rod, the levers 12 and 14 will be restored to their normal positions by the springs 37 to elevate the platen.

The levers 12 and 14 are all arranged in parallel relation and are maintained in such relation at all points in their swinging movements. The connection between the levers 12 and 14 on each side of the platen causes parallel movements to be given to said levers by the turning movement of the actuating rock shaft 36 or by the vertical movements of the bar 58. The connection between the levers 12 and between the levers 14 which may be said to be arranged in pairs, the members of which are located in opposed relation on opposite sides of the platen, causes the levers of each pair to be maintained in substantially parallel relative positions during their swinging movement.

By the swinging movements of the platen supporting levers, movements of translation are imparted to the platen, and, in the present embodiment of the invention, these movements are substantially perpendicular to the general plane of the platen.

It will be noted from an inspection of Figs. 2 and 3 of the drawings that, after the platen raising mechanism starts to raise the platen from the position shown in Fig. 3, the point of contact of each of the lever 12 with the lower side of the platen moves toward a line substantially perpendicular to the platen and passing through the axis of the lever, until the platen reaches its uppermost position. Thus each of the levers 14 exerts an increasing mechanical advantage on the platen during the upward movement thereof from the position shown in Fig. 3.

It is to be understood that the terms "raising" and "lowering" applied to the movements of the platen, are not to be regarded as restrictive but that these terms apply generally to movements of a platen toward and from its operative position, whether or not these are vertical movements.

Having explained the nature and object of the invention and having specifically described a construction embodying the invention in its preferred form, what is claimed is:

1. In a typewriting machine, a platen frame, a substantially flat platen mounted in said frame for movements of translation in directions substantially perpendicular to the plane of the platen, means for movably supporting the platen in said frame comprising four or more parallel supporting levers arranged two on each side of the platen, to support the platen by contact, upon which levers the platen rests and is held in place by gravitational action, the levers on opposite sides of the platen being arranged in pairs the members of which swing on coincident axes, means for connecting said levers for movement in unison in the same direction about the several axes thereof comprising links for connecting the levers on each side of the platen to maintain the same in parallel relation during their movements, means for maintaining the levers at one end of

the platen in parallel relation during their movements comprising a rock shaft located adjacent the forward end of the platen frame in a position transverse thereto, arms fixed to the rock shaft and links connecting the arms on the rock shaft respectively with said latter two levers, a hand lever secured to the rock shaft to turn the same to swing said supporting levers to raise and lower the platen and a stop for limiting the movement of the rock shaft in a direction to lower the platen.

2. A typewriting machine comprising a platen frame, a plate-like platen mounted for movement in said frame in directions substantially perpendicular to the plane thereof, means for supporting the platen on said frame comprising three or more supporting levers pivoted respectively to the frame on axes extending in the same direction substantially parallel to the plane of the platen and each arranged to support one point in the platen by contact therewith for engaging and supporting the platen, each lever having contact surfaces fixed with relation to the lever and located at different distances from the axis of the lever and arranged to be brought successively into engagement with the platen by the pivotal movement of the lever, upon which levers the platen rests by gravitational action, means for connecting said levers for movement in unison in the same direction about the several axes thereof and manually controlled means for swinging said levers in unison to raise and lower the platen.

3. A typewriting machine comprising a platen frame, a substantially flat platen mounted for movement bodily in said frame in directions substantially perpendicular to the plane thereof toward and from writing position, means for supporting the platen for said movement in the frame comprising two supporting levers located forwardly of the transverse central line of the platen on opposite sides thereof and pivoted to the platen frame on coincident axes and arranged to support the platen by contact therewith, the platen resting on said levers and being held in place by gravity, and two supporting levers located to the rear of said central line on opposite sides of the platen and pivoted to the platen frame on coincident axes substantially parallel with the axes of said first levers and arranged to support the platen by contact therewith, the platen also resting on said levers and being held in place by gravity, means for connecting all said levers for movement in unison in the same direction about the several axes thereof, a cross bar connecting two of said levers on opposite sides of the platen and vertically movable to raise and lower the platen and treadle operated means for operating said cross bar to depress the platen.

4. In a typewriting machine, a platen frame, a substantially flat platen mounted in said frame for movements of translation in directions substantially perpendicular to the plane of the platen, means for movably supporting the platen in said frame comprising four or more parallel supporting levers arranged two on each side of the platen, to support the platen by contact and each having an upper and a lower arm, upon the upper arms of which levers the platen rests and is held in place by gravitational action, the levers on opposite sides of the platen being arranged in pairs the members of which swing on coincident axes, means for connecting said levers for movement in unison in the same direction about the several axes thereof comprising links for con-

necting the levers on each side of the platen to maintain the same in parallel relation during their movements, means for maintaining the levers nearer the forward end of the platen in parallel relation during their movements comprising a horizontal rock shaft mounted adjacent the forward end of the platen frame in a position

transverse thereto, arms mounted on and extending upwardly from said rock shaft, pull links connecting said arms with the lower arms of the two adjacent supporting levers, and a hand lever attached to the rock shaft for actuating the rock shaft.

OSCAR J. SUNDSTRAND.
